CALCULATING MACHINE

Robert R. Henderson, Detroit, Mich., assignor to
 Burroughs Adding Machine Company, Detroit,
 Mich., a corporation of Michigan

Application March 12, 1934, Serial No. 715,074

6 Claims. (Cl. 235—62)

This invention relates to calculating machines and is particularly adaptable to key responsive calculators.

Calculators having two or more registers are usually provided with mechanisms by which the totals from one register may be transferred to another register. It is frequently desirable, particularly when computing items involving fractions, to transfer only a portion of the total from one register to another. Accordingly it is the purpose of this invention to provide a control for the total transfer mechanism whereby predetermined digits or columns only will be transferred and certain other columns will not be transferred during a total transfer operation. Other objects and their resultant advantages will appear from the following description.

The utility and applicability of this invention will be better understood by first explaining a typical use of the invention. The invention is of particular utility in general calculating work involving the multiplication of small amounts involving decimals and fractions. In certain transactions of this nature it is desirable to drop the decimal digits or columns of smaller denominations than hundredths or cents before the total is transferred from one register to the other.

A specific example of an application of this invention occurs in accumulating merchandise sales, such as items like 25 yards of cloth at 12 $\frac{3}{4}$ ¢ per yard. Ordinarily when using a calculating machine for listing amounts involving fractions or decimals of this character the five right or lowest order register pinions are used for the decimal digits and the remaining pinions to the left are used for the whole digits such as dollars. In making such a calculation of 25 yards at 12 $\frac{3}{4}$ ¢, according to one method of operation, the operator would transpose the 12 $\frac{3}{4}$ ¢ to .12750 and enter this amount in the front register of the machine by depressing the corresponding keys in the five right columns of the machine as numbered in Fig. 1. After setting up the amount .1275 in the left four of the five decimal columns or in columns 2, 3, 4, 5, starting from the right, the amount is multiplied by 25. The front register then contains the amount 3.18750. Any method of operation for performing the multiplication may be used.

It is customary in business to bill only to the nearest cent, and to add one cent to the cents column if the fraction is over a half and dropping the fraction if it is under the half. Accordingly the amount billed for the 25 yards of cloth

would be \$3.19. Therefore, \$3.19 and not 3.18750 should be transferred to the rear register.

To correct the totals in the one register prior to a transfer to the second or grand total register (when calculating in fractions of cents), it is occasionally necessary to raise the decimal amount in the first register to the exact amount placed on the invoice. In order to do this the No. 5 key in column 3 is depressed to add five mills or five units in the third from the right column of the machine. If the column already contains five or more units a carry will be made into the next column to the left, making the necessary correction. Of course, if the third column from the right does not contain five units no carry will take place and depression of the No. 5 key will not create a carry in the cents column. This key is known as the "full cent" key and is usually provided with a key top of distinguishing color such as red, so that it may be readily detected by the operator.

After the depression of the full cent key in the foregoing example the register would indicate 3.19250. If this amount as indicated were transferred to the second register to be accumulated in the grand total it is obvious that a total taken from an accumulation of such items would still not give the same results as the total of the invoices sent out which invoices included only the dollars and cents. Therefore, it is desirable to provide some means to prevent the transfer of the three right columns indicating 250 to the second register when a total transfer is made from the first to the second register so that the second register will indicate the sum 3.19. It is, of course, desirable that the mechanism for preventing the transfer of the three right columns be selectively operable so that the machine may be used in its normal state for ordinary calculating purposes.

Having in mind the foregoing typical example of one use of this invention, the mechanism for accomplishing the desired results will be described in connection with the drawings in which,

Figure 1 is a perspective plan view of a calculating machine illustrating the keyboard and showing the full cent key and the special key for controlling the transfer;

Fig. 2 is a right side sectional elevation of the calculating machine illustrating the mechanism for controlling the transfer from front to rear register;

Fig. 3 is an enlarged perspective view of the blocking means for preventing transfer in the three right register columns; and

Fig. 4 is a right side elevation with the casing removed illustrating the transfer key and associated mechanism.

General calculator features

The calculating machine and mechanism is similar to that shown in the Pasinski Patent 1,909,714 issued May 16, 1933, and in the co-pending application of Walter Pasinski, Serial No. 694,550, filed October 21, 1933.

For an understanding of the details of the calculator mechanisms involved in the machine of this invention, reference is made to the foregoing Pasinski patent and Pasinski application.

The usual depressible amount or digit keys 10 arranged in banks are supported between the upper keyboard plate 11 and the lower strip 12 (Fig. 2), the keys being normally urged upwards by compression springs 13. The keys are provided with laterally extending projections 14 adapted when the keys are depressed to engage upwardly extending lugs 16 formed on index bars 17 of the differential mechanism, there being an index bar 17 for each bank of keys. The lower ends of keys 10 engage slots 18 formed in slides 19 whereby the slides 19 are moved rearward against the tension of springs 21, there being a slide and spring for each bank of keys. Each slide 19 has a downwardly projecting finger 22 adapted to engage a cross bail 23 provided with a downwardly extending arm 25 adapted to engage and close a pair of switch contacts 26 connected in the motor circuit for starting and stopping the driving motor M, the switch being normally disengaged by the urge of bail 23 which is spring actuated. Under depression of any key 10 the bail is rocked and the switch contacts are closed to start the motor.

Motor M through suitable gears (not shown) drives a main operating shaft 29 which latter shaft extends across the entire width of the machine. Fixed to shaft 29 in each of the various banks of the machine is a toothed ratchet disk 31 (Fig. 2) which is rotated counterclockwise as shown in Fig. 2 by motor M. A pawl 32 engages each ratchet 31 under certain conditions to connect index bars 17 to ratchet 31 so as to be driven by motor M. For this purpose slide 19 is connected by an arm 33 to a latch mechanism 34 as shown in the heretofore mentioned Patent No. 1,909,714, which mechanism normally holds pawl 32 disengaged from ratchet disk 31, but which upon depression of an amount key and the resulting rearward movement of slide 19 releases the latch mechanism 34 to permit pawl 32 to engage ratchet 31.

The forward end of bar 17 is pivotally connected to a toothed actuator rack 40 engaging a gear 41 which carries a pawl 42 (Fig. 2). Pawl 42 engages studs 43 carried by a gear 44 when gear 41 is rotated counterclockwise but ratchets over these studs when gear 41 is rotated clockwise. Gear 44 is in constant mesh with a gear 46 which rotates the front or item entering register pinions 47. It will be understood that there is a pinion 47 and a set of gears and pawl for each bank of amount keys, the plurality of pinions making up the registering mechanism as a whole. The register pinions are visible through a sight opening 48 in the casing 49.

Accumulating operation

Upon depression of an amount key 10, slide 19 is moved rearwardly, thereby connecting the

motor contacts to start the motor which in turn drives the main shaft 29 and index bar 17 forward, the pawl 32 having been released by movement of latch 34. Bar 17 moves forward until stopped by the depressed amount key, which is locked in depressed condition. Upon forward movement of index bar 17, pawl 42 carried by gear 41 (Fig. 2) is operated in a clockwise direction and ratchets over studs 43. Upon return movement of the index bar 17 gear 44 is rotated counterclockwise by engagement of pawl 42 with studs 43 and accordingly pinion gear 46 and pinion 47 are rotated to accumulate the amount determined by the depressed amount key in the front or item entering registering mechanism.

Rear register

A rear register which may be termed a grand total register is provided at the rear of the machine (Figs. 1 and 2) and contains a plurality of register pinions 51 visible through a sight opening 52 in casing 49. The rear register mechanism is constructed exactly the same as the front register mechanism and is indexed by a differential mechanism including actuating racks 53 pivoted at 54 which engage pinions 55 for driving the register pinion 51 as in the case of the front register. Accordingly, amounts may be indexed into the rear register in exactly the same manner as in the front register, i. e., upon differential clockwise movement or racks 53 normally urged counterclockwise by springs 56. The rear register does not, however, receive amounts directly from the keys as does the front register but receives amounts which are transferred to it from the front register as will now be explained.

Total transfer mechanism

Means are provided for transferring totals from the front register pinions 47 to the rear register pinions 51 so that additional items can be accumulated in the front register and transferred into the rear register for a grand total.

Each register pinion 47 of the front register is provided with a small back cam 61 (Figs. 2 and 3) of uniform rise, which cam is engaged by a stud 62 carried by the upper end of a lever 64 pivoted at 65 and is urged clockwise by the spring 66 into engagement with the cam. Stud 62 engages the low point of the cam in zero position of the pinion 47 as shown in Fig. 3, and is swung outwardly upon progressive rotation of the register pinions to rock lever 64 counterclockwise about its pivot 65. It will be understood, of course, that there is a lever 64 for each order of pinions or bank of amount keys. A lower or depending arm 63 of each lever 64 is connected with a link 67 which is pivotally connected at its other end to an arm 68 of a yoke 69. Yoke 69 is pivoted on a cross shaft 71 and is provided with a differential cam lever 72 notched as at 73 which notches are engaged by lug 74 formed on the forward end of a connecting link 76 slidably supported at its front end by a stud 77. Link 76 extends rearwardly and upwardly to the rear of the machine where it is pivotally connected at 78 to a downwardly extending arm 79 journaled on shaft 54 and secured to the actuator rack 53. The rear register is thereby connected to the front register by a second differential mechanism and is actuated from the front register through this second differential mechanism in accordance with the position of the front register pinions 47.

In normal position, that is, when amounts are not being transferred into the rear register from the front register, racks 53 are urged counterclockwise by springs 56 but are retained against movement by a cross bail or shaft 81 supported in arms 82 at each side of the machine. Cross bail 81 engages the lower hooked end 79 of the racks 53 to control movement of the latter and of links 76 which are secured to the lower ends 10 79 of racks 53.

To permit transfer of an accumulated total in the front register to the rear register, cross bail 81 must be moved rearwardly to permit movement of actuator racks 53 in accordance 15 with the permissible movement of links 76, as determined by engagement of lugs 74 with the notches 73 in the differential levers 72. The notches engaged by lugs 74 are, of course, determined by the position of the corresponding snail 20 back cams 61 which in turn are positioned in accordance with their associated register pinions 47.

During a transfer operation when an amount 25 is to be transferred from the front register to the rear register the cross bail 81 is moved rearwardly to allow racks 53 to move counterclockwise under urge of springs 56 until the racks are arrested by engagement of lugs 74 with the particular notch 73 in cam or index lever 72 as determined by the position of the associated snail 30 back cam 61 of the corresponding register pinion positioned in accordance with the depression of a key. Upon return movement of cross bail 81 the actuator rack 53 is returned to initial position and the corresponding register 35 pinion 51 will be rotated to increase the reading thereon, the amount determined by the position of the front register pinion. During the accumulation of items in the front register the rear register mechanism is prevented from movement 40 because of cross bail 81 although the index lever 72 is indexed for each movement of its corresponding register pinion.

45 Control keys

The illustrated machine is provided with a 50 bank of control keys including a transfer key "T" (Figs. 1 and 4). The transfer key is operated to cause a transfer of the total accumulated in the front register to the rear register.

The transfer key is in the form of a finger 55 bar attached to a sliding key stem 85 intermediate whose ends is connected a crank 86, pivoted at 87 (Fig. 4). The other end of crank 86 is connected to one end of a link 88 normally urged to the rear or the right as shown in Fig. 4 by spring 89. The rear end of link 88 is slidably supported by a stud 91 and terminates in a lug 92 which controls the actuator 53 and the 60 bail 81 as will later be explained.

To energize the motor upon depression of the transfer key, a slide 95 (Fig. 4) is provided having a cam slot 96 into which projects a pin 97 carried by a lever 98 pivoted at 99. Upon forward movement of slide 95, caused by engagement of a pin 101 connecting crank 86 to key stem 85, with slide 95, pin 97 is cammed downwardly swinging lever 98 downwardly in a clockwise direction. The rearward end of lever 98 is provided with a downwardly projecting hook portion 102 which engages a laterally projecting pin 103 extending from an arm 104 extending upwardly from bail 23, whenever slide 95 moves from its rearward position to its forward

position. Accordingly, when the transfer key is depressed the motor is energized by reason of movement of slide 95 actuating bail 23 which in turn closes the switch 26.

The transfer key also operates any suitable 5 clutch (not shown) for controlling operation of a transfer from one register to the other. For this reason the rear end of slide 95 is provided with an integral lug 106 (Fig. 4), which engages the upper arm 107 of a three-armed 10 lever pivoted at 108 to bell crank lever 109. When in normal position, a lower hooked end 110 of bell crank lever 109 lies beneath the nose 111A of a clutch control disk 111, on shaft 29. When the slide 95 is moved to the left or forward 15 position, the hooked end 110 clears the nose of clutch disk 111 and releases the clutch for rotation which causes shaft 29 to rotate. Shaft 29 carries a cam 112, shown in dotted lines in Fig. 3, which cam engages a roller 112b on a 20 lever 112c pivoted intermediate its ends. Lever 112c extends rearwardly and engages shaft 81 to withdraw the latter rearwardly and permit a 25 total transfer from the front register to the rear register, as previously described. Shaft 29 also carries a second cam 112a shown in dotted lines in Fig. 3, which cam engages a roller 114a on lever 114. Lever 114 extends upwardly and is connected to the clearing link 114b for controlling clearing of the front register after a 30 transfer has been made. For further details of the foregoing mechanism, reference is made to the heretofore mentioned Pasinski application.

Transfer blocks

35

As previously stated, when using the machine for transactions working decimals or fractions, control means are provided which when operative prevent the transfer of the first three lowest orders of the machine from the front register into 40 the rear register. The foregoing is accomplished by preventing rearward movement of links 76 and racks 53 in the first three right columns of the machine as viewed by the operator in order to prevent accumulation in the rear register in those 45 predetermined columns during the transfer operation.

Referring to Fig. 3, a bail 115 is pivotally supported on a shaft 71 and has three upwardly extending hooks 116, each of which is adaptable 50 to one of the lugs 74 of the three first columns of the machine. A stud 117 extends outwardly from the right end of yoke 115 and is in constant engagement with the forked end 118 of a lever 119 pivoted at 121 to the lower end of a control 55 key 122. This control key extends through the keyboard at the right side of the machine and terminates in a key top 123. The shank of the key is provided with a notch 124 to latch the key in depressed condition by engagement with the 60 keyboard. The lower end of the key is slotted to straddle shaft 71, and is formed with a forwardly extending arm 126 to which a spring 127 is attached normally urging the key upward and in a clockwise direction to urge notch 124 into 65 locking engagement with the keyboard.

Lever 119 pivoted to the key is formed with an upwardly extending arm 128 urged into engagement with a stud 129 projecting from the key by means of a spring 131. Spring 131 and lever 119 70 pivoted to the key provide a yielding connection between the key and the bail.

With the machine in normal position, i. e., with the control key in its upper position the 75

transfer blocking means is inactive and the machine may be used in a normal way for accumulating amounts. In this position yoke 115 is in the position illustrated in Fig. 3 where the hooked ends 116 do not engage lugs 74. When control key 122 is depressed to where its notch 124 engages the keyboard, yoke 115 is rocked counterclockwise (Fig. 3) through the yielding connection of lever 119 and spring 131, thus moving the hooked ends 116 directly in the rearward path of travel of the three links 76 for the first three lowest columns or orders of the machine. In this position yoke 115 prevents any rearward movement of the three links 76 for the first three lowest columns of the machine but does not in any way affect the rocking or indexing of the index levers 72.

Accordingly, with the key 122 in depressed position links 76 in the first three columns of the machine are prevented from moving during the transfer operation and do not engage index levers 72. Therefore, no amount can be entered in the first three columns of the rear register. During the transfer operation, however, levers 72 are permitted to return to their zero position during the cancelling or zeroizing movement of the front register.

The rear edges of the hooked ends 116 of yoke 115 are beveled to provide an angular or cam-like edge to rock yoke 115 clockwise in the event that the control key 122 is mis-operated such as by being depressed during a transfer operation while the links are in their rearward position. If this occurs lugs 74 upon their return stroke to forward positions engage the bevelled edge of the hooked ends and rock yoke 115 clockwise. This is permissible because of the yielding connection provided between the pivoted lever 119 and the key stem 122.

From the foregoing description it will be apparent that should the operator desire to accumulate fractions or decimals and transfer only the full cents it is merely necessary to depress the "full cent" key to insure that the full cent is entered into the machine and then depress the control key top 123 to prevent transfer of the amounts indicated in the last three columns of the front register to the rear register. When it is desired to return the machine to normal condition for normal calculations it is only necessary to unlatch the control key 122 and the machine is returned to normal condition.

It will be obvious to those skilled in the art that the foregoing invention is adaptable to many applications and uses and that the mechanism disclosed is given by way of example only, and does not limit the invention as defined in the claims appended hereto.

I claim:

1. A calculating machine having depressible amount keys, differential mechanism controlled by said keys, a register mechanism having pinions controlled by said differential mechanism, a second register mechanism, means for transferring totals from said first register to the second comprising independent means for transferring the indication of each register pinion of one register to the corresponding pinion of the second register, and adjustable means operable when in one position to prevent the operation of predetermined elements of said independent means upon transfer operations.

2. A calculating machine having depressible amount keys, differential mechanism controlled

by said keys, a register mechanism having pinions operated from said differential mechanism, a second register mechanism, means for transferring totals from said first register to the second comprising a second differential mechanism, means for positioning said second differential mechanism in accordance with the position of the pinions of said first register, means for actuating said second register mechanism from said second differential mechanism, and means for blocking portions of said actuating means against operation upon transfer operations. 5

3. A key responsive calculating machine having banks of depressible amount keys, an index bar for each bank of keys movable to differential 15 positions determined by the keys depressed, a register mechanism operated from said bars, a second register mechanism, mechanism for transferring totals from the first register to the second, and means for preventing operation of 20 predetermined portions of said transferring mechanism upon transfer operations.

4. A key responsive calculating machine having banks of depressible amount keys, an index bar for each bank of keys movable to differential 25 positions determined by the keys of its bank, a register mechanism having pinions operated from said bars, a second register mechanism, means for transferring totals from said first register to the second comprising a second differential 30 mechanism, means for positioning said second differential mechanism in accordance with the positions of the pinions of said first register, means for actuating said second register mechanism from said second differential mechanism, 35 and adjustable means operable when in one position to prevent operation of predetermined portions of said actuating means upon transfer operations.

5. A key responsive calculating machine having 40 banks of depressible amount keys, an index bar for each bank of keys movable to differential positions determined by the keys of its bank, a register mechanism having pinions operated from said bars, a second register mechanism, means 45 for transferring totals from said first register to the second comprising a second differential mechanism, means for positioning said second differential mechanism in accordance with the positions of the pinions of said first register, means for connecting said second register mechanism to said second differential mechanism, and adjustable means operable when in one position to disable predetermined portions of said connecting means upon transfer operation. 55

6. A key responsive calculating machine having banks of depressible amount keys, an index bar for each bank of keys movable to differential positions determined by the keys of its bank, a register mechanism having pinions operated from 60 said bars, a second register mechanism, means for transferring totals from the first register to the second comprising a second differential mechanism, means for positioning said second differential mechanism in accordance with the 65 positions of the pinions of said first register, means connecting said second register mechanism to said second differential mechanism, and adjustable means common to a plurality of connecting elements and operable when in one position to disable said connecting elements upon transfer operations. 70
